UNITED STATES PATENT OFFICE.

HENRY ELLIS WEAVER, OF DENVER, COLORADO.

CARBURETER.

1,209,788.

Specification of Letters Patent. Patented Dec. 26, 1916.

Application filed November 27, 1915. Serial No. 63,806.

To all whom it may concern:

Be it known that I, HENRY ELLIS WEAVER, a citizen of the United States, residing at Denver, in the county of Denver and State of Colorado, have invented a new and useful Carbureter, of which the following is a specification.

The present invention appertains to carbureters, and aims to provide a novel and improved apparatus of that character.

It is the object of the invention to provide a carbureter of novel and improved construction for the production of carbureted air, which can be used generally for lighting and heating purposes, the present gas being produced artificially by the passage of air under pressure through gasoline or other volatile hydrocarbon.

It is also within the scope of the invention to provide a carbureter of the nature indicated which is comparatively simple and inexpensive in construction, as well as being practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:—

Figure 1 is a side elevation of the apparatus. Figs. 2 and 3 are vertical sections taken on the lines 2—2 and 3—3, respectively, of Fig. 1. Fig. 4 is a sectional detail taken on the line 4—4 of Fig. 3.

In carrying out the invention, there is employed a pair of upright cylindrical tanks 1—2 set on end adjacent one another. These tanks are preferably constructed of sheet metal and have the convexed heads 3 and bottoms 4. Each tank is also provided therein between its upper and lower ends with a horizontal sheet metal partition 5 having its margin riveted or otherwise secured to the side walls of the tank.

Disposed within each tank above the partition 5 thereof is a hood 6, preferably constructed of sheet metal, and having its rim or lower end seating upon the partition 5.

The hood 6 is of slightly smaller diameter

than the tank to provide an annular space therebetween, and angular spacing members 7 are riveted or otherwise secured to the rim of the hood adjacent the lower end thereof and project outwardly to contact with the tank for spacing the hood therefrom. Angle members 8 are riveted or otherwise secured to the tank and project over and contact with the upper end of the hood for holding the hood seated upon the partition. The hood 6 has annular series of apertures 9 establishing communication between the interior of the hood and the annular space between the hood and tank. The hood 6 of tank 1 has only lower apertures 9. Thus, the liquid level within the hood 6 of tank 1 will be lower than the liquid level within the hood of tank 2. This shows how the hoods can be provided with apertures at different points thereof, according to the circumstances.

A vertical pipe or conduit 10 is engaged centrally through each partition 5 axially or concentrically within the respective tank, so that the upper end of the pipe 10 projects within the hood 6, while the lower end depends from the partition 5. The lower end of the pipe 10 is provided with a flared mouth 11, and the pipe 10 has an annular series of apertures 10' immediately above the partition 5.

Within each tank, there is an air chamber 12 below the partition 5 and above the lower end of the pipe 10, a second air chamber 13 within the upper portion of the hood 6 above the upper apertures 9, and a third air chamber 14 within the upper portion of the tank above the hood. A pressure gage 15 is attached to each tank in communication with the chamber 14 to indicate the pressure of the gas within said chamber.

Each tank is provided with diametrically opposite vertical by-pass pipes 16 having their ends attached to the respective walls of the tank adjacent the bottom 4 thereof and immediately above the partition 5. Each of the pipes 16 has a controlling valve 17, and one pipe 16 of each pair is provided at its lower end with an outstanding nozzle 18 or branch 18 having a controlling valve 19, said branch 18 being normally closed by a removable screw cap 20.

Air under pressure is supplied within the tank 1 adjacent the bottom thereof and be-

low the chamber 12, by an air supply pipe 21 extending to an air compressor (not shown) engaged through one wall of the tank 1 adjacent the bottom of said tank. The pipe 21 is provided with a pressure or escape valve 22 having an outlet branch 23, whereby when the air pressure exceeds the desired amount, the surplus air is let out through the branch 23 to the atmosphere. This prevents an excessive pressure of the air and gas. The pipe 21 is also provided with a check valve 24 adjacent the tank 1, to allow the air to flow into the tank, but to prevent the retrograde flow of the air and liquid from the tank. 15 The pipe 21 also has a controlling valve 25. With the tank 1, the pipe 21 has a cruciform air outlet member 26 embodying the radial tubular arms 26' attached to a coupling 26^a which in turn is attached to the end of the 20 pipe 21, the outer ends of the arms 26' being closed by caps 26^b. The outlet member 26 has upper apertures.

The upper end of the tank 1 is provided with outlet means which communicate with 25 the lower end of the second tank 2, and to this end, the head 3 of the tank 1 is provided with diametrically opposite upstanding outlet pipes 27 which have secured thereon the 30 couplings 28—29. The coupling 28 is a T-coupling whereas the coupling 29 is a cruciform or X-shaped coupling provided with a removable closure plug 30 which can be removed for allowing the tank to be filled with gasolene or other volatile hydrocarbon. The 35 couplings 28—29 are connected by an equalizing pipe 31, and said couplings have attached thereto, the upper ends of a pair of opposite inclined pipes 32 which have their lower ends connected to diametrically opposite 40 site walls of the tank 2 adjacent the bottom 4 thereof. The gas in the chamber 14 of the tank 1 therefore flows into the lower portion of the second tank 2 by way of the pipes 32.

The upper end of the tank 2 is provided 45 with a gas outlet embodying a coupling 33 attached to the upper end of the said tank, and the gas main or pipe 34 is connected to the coupling 33. The coupling 33 has a removable plug 35 which when removed allows 50 the gasolene or volatile hydrocarbon to be poured into the tank 2.

In operation, the tanks are first filled with 55 the gasolene or other volatile hydrocarbon, which will fill the tanks as indicated in Figs. 2 and 3. The liquid will fill the lower portion of the tanks up to or slightly above the lower ends of the pipes 10, which provides the confined air or gas chambers 12, and the liquid will also fill the hoods 6 up to 60 or slightly above the upper apertures 9 thereof, the partition 5 preventing the liquid from flowing directly downward. The liquid also fills the tank outside of the hoods 6. The pressure of air trapped within the 65 various chambers prevents the inflow of

liquid thereinto above the liquid entrance openings, except to such a distance as the volume of trapped air may be reduced due to the external liquid pressure head. The pipes 10 provide means of communication 70 between the liquid in the lower ends of the tanks and the chambers 13, and the apertures 9 establish communication between the liquid in the hoods 6 and the chambers 14, the air or gas in being forced from one 75 chamber to the other being compelled to flow through the liquid whereby the air will become saturated with the volatile liquid, to produce the carbureted air which may be used for lighting and heating purposes generally, for running internal explosion engines, and the like. The air is forced through the pipe 21 from a suitable compressor (not shown) and is forced through the apertures of the member 26 into the 80 liquid within the lower portion of the tank 1. The air then rises through the liquid into the lower end of the respective pipe 10 and up through said pipe into the respective chamber 13. From the chamber 13, the air 90 is forced through the apertures 9 and through the liquid surrounding the respective hood 6 into the chamber 14 of the tank 1. From the said chamber 14 the gas is forced by way of the pipes 32 into the liquid in the lower end of the second tank 2, and the gas takes the same course through the tank 2 as in the tank 1. The gas accumulates in the upper chamber 14 of the tank 2 95 and is then discharged into the gas main or pipe 34 by which it is led to the point of consumption.

The valves 17 when opened permit the liquid to flow through the by-pass pipes 16, whereby the liquid may flow past the partitions 5 more readily. The valves 19 are ordinarily closed, and when the caps 20 are removed; the valves 19 can be opened for draining the tanks, and furthermore, when an oil or heavier hydrocarbon is used, the same may be forced into the tanks by way of the branches 18 and pipes 16. It is evident, also, in the operation of the device that the air will flow from the pipes 10 through the apertures 10' into the liquid within the hoods 6. The superposed liquid chambers of each tank are in communication, whereby the liquid can flow from the upper liquid chamber to the lowermost, and there is a gas chamber above each liquid chamber.

The two tanks are practical duplicates of one another, with slight variations, and in some cases but a single tank need be used, and if desired more than two tanks can be connected in series.

The compressor which is used for projecting the compressed air into the tanks, can be run by an engine supplied with the gas, so that independent power is not necessary. The apparatus can be constructed on various 130

scales according to the use to which it is put, and can be used either for domestic purposes or as a commercial plant.

Having thus described the invention, what is claimed as new is:

1. In a carbureter, a tank having a partition therein between its upper and lower ends defining a liquid holding chamber below the partition, means for injecting air into said chamber, a hood seating upon said partition and having its rim provided with apertures, the tank being adapted to be filled with a volatile liquid within and around the hood above the partition, the tank having an upper outlet, and means for conducting air upwardly from said chamber through said partition into said hood.
2. A carbureter embodying an upright tank having a partition therein between its upper and lower ends, a hood seated upon

said partition and having its rim provided with apertures below its upper end, a vertical pipe engaged through said partition and projecting within the hood, the tank being adapted to be filled with a volatile liquid 25 within its lower portion and within and around the hood above the partition, the tank having an upper outlet, and means for injecting air into the lower portion of the tank, said pipe having a flared mouth at its 30 lower end and apertures immediately above said partition.

In testimony that I claim the foregoing as my own, I have hereto affixed my signature in the presence of two witnesses.

HENRY ELLIS WEAVER.
